UNITED STATES PATENT OFFICE.

SAMUEL KRAUS, OF NEW YORK, N. Y., ASSIGNOR TO THE EAGLE PENCIL COMPANY, OF SAME PLACE.

DESIGN FOR A LEAD-PENCIL.

SPECIFICATION forming part of Design No. 22,415, dated May 9, 1893.

Application filed April 4, 1893. Serial No. 469,075. Term of patent 14 years.

To all whom it may concern:

Be it known that I, SAMUEL KRAUS, of the city, county, and State of New York, have invented a new and original Design for Lead-

5 Pencils, of which the following is a specification.

The design consists of a lead pencil, the body of which terminates in a tip surmounted by a female dancing figure.

10 In the accompanying drawing, which represents a pencil embodying my design, A is the body of the pencil and B is the tip surmounted by the dancing figure.

What I claim, and desire to secure by Letters Patent, is—

15 The design for lead pencils substantially as described and shown.

In testimony whereof I affix my signature in presence of two witnesses.

SAMUEL KRAUS.
